THE NORRIS-PETERS CO., WASHINGTON, D. C.

UNITED STATES PATENT OFFICE.

GEORGE T. SPEAR, OF LAKELAND, FLORIDA.

CRIB ATTACHMENT FOR BEDS.

No. 918,789.

Specification of Letters Patent.

Patented April 20, 1909.

Application filed January 25, 1908. Serial No. 412,617.

To all whom it may concern:

Be it known that I, GEORGE THOMAS SPEAR, a citizen of the United States, residing at Lakeland, in the county of Polk and State of Florida, have invented certain new and useful Improvements in Crib Attachments for Beds, of which the following is a specification, reference being had to the accompanying drawings.

10 My invention relates to improvements in crib attachments for bedsteads and it consists of the novel features of construction and the combination and arrangement of parts hereinafter described and claimed.

15 One object of the invention is to provide a baby bed or crib support of simple, practical and comparatively inexpensive construction which is revolutely mounted so that the crib may be swung inwardly across the bed or outwardly along side of or away from the same.

20 Another object of the invention is to provide a device of this character in which the crib support may be quickly and easily detached from the bed without loosening any screws or other fastenings.

25 A further object of the invention is to provide a device of this character in which the parts may be adjusted for application to beds of different size and also adjusted for beds of different width and height.

The above and other objects of the invention are attained in its preferred embodiment illustrated in the drawings, in which—

Figure 1 is a perspective view of a bed 35 showing my improved crib attachment applied thereto, the crib being shown arranged over the bed in full lines and swung out along side of the same in dotted lines; Fig. 2 is a vertical section through the attachment and the side rails of the bed; Fig. 3 is a detail perspective view of the crib support and the upper end of its revolving standard; Figs. 4 and 5 are detail sectional views taken respectively on the planes indicated by the 45 lines 4—4 and 5—5 in Fig. 2; Fig. 6 is a detail section showing the clamping screw for fastening one of the legs of the crib; Fig. 7 is a detail perspective view of one of the bed rail engaging clamps; and Fig. 8 is a perspective view of the crib showing its supporting legs lowered.

In the drawings B denotes a bed having side rails R and 1 denotes my improved crib attachment which consists of a baby bed or 50 crib body 2, a support 3 for the same, a

revoluble standard 4 on which the crib support is vertically adjustable and a bearing or support 5 in which the standard is mounted for rotation and which is adapted for attachment to the side rails of a bed of any form 60 and construction.

The detachable support 5 is in the form of a step or socket bearing 6 provided upon one end of a cross bar 7 adapted to be passed transversely across the bed beneath the 65 rails R and to be secured thereto by clamps 8. Said cross bar is preferably composed of two or more sections hinged together as at 9 or otherwise jointed so that the standard can be folded when removed from the bed. Said 70 cross bar is of greater length than the width of the bed and when the clamps 8 are loosened may be slid longitudinally to dispose the socket bearing 6 at a greater or less distance from one of the bed rails R. 75

The clamps 8 are similar and each consists of two similar members 10 to engage the opposite sides of the bed rail and formed in their lower ends with openings 11 to receive the cross bar 7. The upper ends of the clamp 80 members are reduced and curved to provide crossed arms 12 each having a longitudinal series of apertures 13 to receive a fastening bolt or the like 14. By constructing and uniting the arms 12 in this manner it will be 85 seen that the clamp may be applied to a bed rail of any width and thickness.

The standard 4 has its lower end formed with a reduced pivot portion 15 at the upper end of which is an annular flange or collar 16. 90 The parts 15, 16 are adapted to fit and rotate freely in the similar shaped socket formed in the bearing 6, which latter has a tubular lower portion 17 and an enlarged or flared upper portion 18. This construction allows 95 the standard and the parts which it carries to be readily removed from the bearing without the necessity of loosening any screws, bolts, or other fastenings, when the crib is not needed, the bearing 6, the cross bar 7 and 100 the clamps 8 remaining upon the bed. For the purpose of holding the standard stationary to retain the crib in an adjusted position I preferably provide in the tubular portion 17 of the bearing a set screw 19 which impinges against the pivot 15. The upper end 105 of the standard is formed with a reduced portion 20 having one or more flat faces and on which the crib support 3 is vertically adjustable. In the upper portion of the standard, 110

adjacent to its reduced end 20, is a longitudinal groove 21, the purpose of which will presently appear.

The crib support 3 comprises a head 22 from which project right angular supporting arms 23 having parallel outer portions on which the crib body 2 is removably supported. The head 22 is formed with a vertical opening to slidably receive the upper 10 end 20 of the standard and a set screw 24 is arranged in said head for holding it in an adjusted position. This adjustment enables the crib to be disposed in different horizontal planes according to the thickness of the bed 15 and its covering. The crib supporting arms 23 are reinforced, adjacent to their inner ends, by angular braces 25, the lower ends of which are united to provide a tongue 26 which enters the groove 21 in the standard 20 and which slides therein when the support 3 is adjusted.

The crib body 2 may be of any suitable form and construction and it is preferably removably mounted upon the arms 23 and 25 provided with foldable supporting legs 27. These legs are rotatably mounted upon the ends of the crib so that they may fold up under the bottom of the same and they are adapted to be held in either their lowered position shown in Fig. 8 or their elevated or folded position shown in Fig. 2 by set screws 28 or any other suitable fastening devices. The crib is removably mounted upon the arms 23 by providing upon the sides of the 35 crib longitudinally aligned socket members or sleeves 29 through which the arms 23 are passed. Set screws 30 are provided in one or more of said socket members 29 for the purpose of retaining the crib in an adjusted position upon said arms. The sides 31 of the crib are pivoted at their lower corners as shown at 32 so that they can be swung downwardly when desired. Suitable catches 33 are provided for holding the sides in their 45 upright or closed position.

The construction, use and advantages of the invention will be readily understood from the foregoing detail description taken in connection with the accompanying drawings; 50 and it will be noted that owing to the various adjustments the attachment may be applied to a bed of almost any form and construction and easily manipulated. By mounting the standard for rotation the crib may be readily 55 swung inwardly over the bed within convenient reach of an occupant of the same, as shown in full lines in Fig. 1, or outwardly along side of the bed as indicated in dotted lines. By constructing the pivot of the 60 standard as set forth and arranging it in the bearing socket for ready removal, the crib and its attached support and standard may be quickly taken off of the bed when the crib is not needed, without the necessity of moving the bearing support 5.

While I have shown and described in detail the preferred embodiment of my invention I wish it understood that I do not limit myself to the precise construction set forth and that various changes in the form, 70 proportion and minor details may be resorted to without departing from the spirit or sacrificing any of the advantages of the invention.

Having thus described my invention what 75 I claim is:

1. The combination of a cross bar to extend across the rails of a bed and provided at one end with a bearing, a crib supporting standard revolvably mounted in said bearing and clamps each consisting of opposing members to receive a bed rail between them and having apertures to receive the cross bar and crossed arms formed with apertures adapted to align with each other, and a transverse fastening passed through the aligned apertures. 85

2. The combination of a cross bar to extend across the rails of the bed and provided at one end with a bearing, a crib supporting 90 standard revolvably mounted in said bearing, said cross bar being composed of foldably connected sections and clamping devices for securing the sections of the cross bar to the bed rails. 95

3. The combination of a bearing for attachment to a bed or the like, a standard revolvably mounted in said bearing and having a flat faced upper end and a groove, a crib support having a head apertured to 100 slidably receive the flat faced upper end of the standard and spaced crib supporting arms, braces for said arms having their inner ends united and slidably in the groove in the standard and means for retaining the head in an adjusted position upon the standard. 105

4. The combination of a socket bearing for attachment to a bed or the like and having the tubular portion 17 and the enlarged 110 outwardly flared upper portion 18, a supporting standard having at its lower end the pivot portion 15 and the annular regular projecting flange 16, said pivot portion and flange being mounted for rotation in said 115 socket bearing and readily removable therefrom, and means for preventing the rotation of said standard.

5. The combination of a bearing for attachment to a bed, a standard revolvably mounted in said bearing, and having a reduced upper end formed with a flat face and also having a longitudinal groove, a crib support having a head apertured to slidably receive the reduced upper end of the standard and spaced rib supporting arms, braces for said arms having their inner ends united and slidably in the groove in the standard, and a set screw for securing the head in an 120 adjusted position. 125

6. The combination of a sectional cross bar adapted to engage the rails of a bed, clamps for uniting the sections of the cross bar to the rails of a bed, a socket bearing 5 upon one end of the cross bar, a standard revolubly and removably mounted in said socket bearing, means for preventing the rotation of said standard, a crib support vertically adjustable upon the upper portion 10 of said standard and a crib longitudinally adjustable upon said support.

7. The combination of a cross bar to extend across the rails of a bed and composed of two hingedly connected sections, adjustable clamping devices removably arranged 15 upon the sections of the cross bar and adapted to engage the bed rails, a socket bearing at one end of the cross bar and having a tubular lower portion and an outwardly 20 flared upper portion, a standard having at its lower end a pivot and an annular flange,

said pivot and flange being rotatably mounted in the socket bearing and readily removable therefrom, a set screw in the socket bearing for holding the standard 25 against rotation, a crib support vertically slidable upon the upper portion of the standard and having spaced crib supporting arms, a set screw for retaining the crib support in an adjusted position, a crib provided 30 upon its bottom with tubular sockets to slidably receive the spaced arms of the crib support and set screws in the last mentioned sockets for holding the crib in an adjusted position upon said arms, substantially as described.

In testimony whereof I hereunto affix my signature in the presence of two witnesses.
